Primary Examiner — Joseph Kukella

Assistant Examiner — Francis Wilder

(57) **CLAIM**

The ornamental design for a RF modular assembly for a RF system as shown and described.

DESCRIPTION

FIG. 1 is a perspective view of a RF modular assembly embodying the invention.

FIG. 2 is a front view of the RF modular assembly of FIG. 1.

FIG. 3 is a rear view of the RF modular assembly of FIG. 1.

FIG. 4 is a top side view of the RF modular assembly of FIG. 1.

FIG. 5 is a bottom side view of the RF modular assembly of FIG. 1.

FIG. 6 is a right side view of the RF modular assembly of FIG. 1.

FIG. 7 is a left side view of the RF modular assembly of FIG. 1.

FIG. 8 is a perspective view of the RF modular assembly of FIG. 1 attached to a base module according to an RF system embodying the invention.

FIG. 9 is a front view of the RF system of FIG. 8.

FIG. 10 is a rear view of the RF system of FIG. 8.

FIG. 11 is a top side view of the RF system of FIG. 8.

FIG. 12 is a bottom side view of the RF system of FIG. 8.

FIG. 13 is a left side view of the RF system of FIG. 8; and, FIG. 14 is a right side view of the RF system of FIG. 8. The broken line showing of radio frequency modular assembly for RF System is for the purpose of illustrating portions of the article or environmental structure and forms no part of the claimed design.

1 Claim, 12 Drawing Sheets
